Primary Examiner—Raphael Barkai*Attorney, Agent, or Firm*—Anthony J. Casella; Gerald E. Hespos; Ludomir A. Budzyn[57] **CLAIM**

The ornamental design of an angulated interlocking building element, as shown and described.

DESCRIPTION

FIG. 1 is a top-front perspective view of an angulated interlocking building element in accordance with my design, and showing the building element having a thickness suitable for a vinyl floor tile;

FIG. 2 is a top plan view of the angulated interlocking building element shown in FIG. 1, with the bottom plan view being substantially identical;

FIG. 3 is a front elevational view of the angulated interlocking building element shown in FIG. 1;

FIG. 4 is a rear elevational view thereof;

FIG. 5 is a side elevational view as viewed from the right side of FIG. 2;

FIG. 6 is a side elevational view as viewed from the left side of FIG. 2;

FIG. 7 is a top-front perspective view of a modified embodiment of the design shown in FIGS. 1-6 and having a thickness suitable for a ceramic tile;

FIG. 8 is a top plan view of the angulated interlocking building element shown in FIG. 7, with the bottom plan view being substantially identical;

FIG. 9 is a front elevational view of the angulated interlocking building element shown in FIG. 7;

FIG. 10 is a rear elevational view thereof;

FIG. 11 is a side elevational view as viewed from the right side of FIG. 8; and

FIG. 12 is a side elevational view as viewed from the left side of FIG. 8.
